UNITED STATES PATENT OFFICE.

ISAAC J. COLLINS, OF LANCASTER, OHIO.

DESIGN FOR A PITCHER OR CAN.

42,269.

Specification for Design.

Patented Mar. 12, 1912.

Application filed September 25, 1911. Serial No. 651,303. Term of patent 7 years.

To all whom it may concern:

Be it known that I, ISAAC J. COLLINS, a citizen of the United States, and a resident of Lancaster, in the county of Fairfield and State of Ohio, have invented a new, original, and ornamental Design for Pitchers or Cans, of which the following is a specification, reference being had to the accompanying drawing, forming a part thereof.

In the drawing—Figure 1 is a perspec-

tive view of a pitcher or can showing my new design. Fig. 2 is a top plan view thereof.

I claim:

The ornamental design for a pitcher or can, as shown.

ISAAC J. COLLINS.
